UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed April 13, 1922. Serial No. 552,179.

To all whom it may concern:

Be it known that I, ORA A. COLBY, a citizen of the United States, and a resident of Irwin, in the county of Westmoreland and State of Pennsylvania, have invented a new and useful Improvement in Electric Furnaces, of which the following is a specification.

My invention relates to electric furnaces and particularly to electric-resistance furnaces and it has for one of its objects to provide a relatively inexpensive built-up refractory heating element for an electric-resistance furnace.

Another object of my invention is to provide a built-up refractory resistor having portions of curved form to permit of directing and concentrating the heat generated by said resistor against an object or material to be heated.

Another object of my invention is to provide a built-up refractory resistor having portions of curved form so connected that the current in adjacent portions flows in opposite directions and the current path is relatively much longer than the length of the resistor.

Another object of my invention is to provide resilient means to maintain the portions of the resistor in close operative engagement.

Another object of my invention is to provide an electric-resistance furnace having, in addition to the resistor of the above indicated character, a second resistor connected in series circuit relatively to the first resistor and comprising a plurality of relatively thin, flat refractory plates resiliently maintained in close operative engagement with each other.

In practising my invention, I provide a plurality of flat, relatively thin, refractory resistor members substantially semicircular in arcuate extent located in spaced-apart relation and electrically connected at their ends in such manner that the current will traverse adjacent members in opposite directions. The individual members may be integral or may comprise a plurality of sections. The resistor members are supported by a

portion of the refractory walls enclosing the furnace chamber, and a portion of the roof of the furnace chamber may be supported by the subdivided resistor members. Resilient means are provided to maintain the ends

of the adjacent resistor members in close operative engagement.

A second resistor may be located beneath the convex surface of the hereinbefore described resistor members and may comprise a plurality of relatively thin refractory plates, the built-up resistor having substantially the same length as the first-mentioned resistor and electrically connected thereto at one end, the plates being maintained in close operative engagement by resilient compressing means.

In the drawings,

Figure 1 is a view, in vertical lateral cross-section, of an electric-resistance furnace embodying my invention, taken on the line I—I of Fig. 2.

Fig. 2 is a view, in vertical, longitudinal cross-section, of a furnace taken on the line II—II of Fig. 1;

Fig. 3 is a view, in vertical, lateral cross-section, of an electric-resistance furnace embodying a modification of my invention;

Fig. 4 is a view, in vertical, longitudinal cross-section of the furnace illustrated in Fig. 3, taken on the line IV—IV thereof.

Fig. 5 is a view, in vertical, lateral cross-section of another modification of my invention;

Fig. 6 is a view, in vertical, longitudinal cross-section of the furnace illustrated in Fig. 5, taken on the line VI—VI thereof;

Fig. 7 is a view, in side elevation, of a portion of a resistor member;

Fig. 8 is a view, in side elevation, of the member illustrated in Fig. 7;

Fig. 9 is a view, in side elevation, of a resistor member of arcuate form employed to connect oppositely disposed members illustrated in Figs. 7 and 8;

Fig. 10 is a top plan view of the resistor member illustrated in Fig. 9 and Fig. 11 is a view, in front elevation, of a still further modification of a resistor member.

Referring particularly to Figs. 1 and 2 of the drawings, an electric-resistance furnace, designated by the numeral 11, comprises a suitable metallic framework or skeleton 12, provided with supporting members 13 suitably secured thereto. An outer lining 14, located within the framework 12, comprises a plurality of bricks or blocks of a suitable heat-insulating refractory material. An inner lining 15 comprises a plu-

rality of bricks or blocks of a suitable refractory, high-temperature-resisting material usually employed in the art, the bricks or blocks constituting the two linings being 5 so shaped and disposed as to provide a furnace chamber 16 of any suitable or desired contour and dimensions.

As it is desired to concentrate the heat generated by the heating element located in 10 the furnace chamber 16 at the top portion thereof, within a relatively small volume, I employ a heating element of arcuate form substantially semicircular in extent and comprising a plurality of refractory side members 15 17, each of substantially U-shape, with the two end portions thereof of arcuate form, as may be noted particularly by reference to Fig. 7 of the drawings. The angular extent of each of the members 17, may be 20 approximately 60° and two sets of members 17 are located in spaced-apart relation at the top of the furnace chamber 16, with their lower or middle portions resting upon suitable ledges 18 provided by the bricks or 25 blocks of the inner lining 15. In order to electrically connect the spaced-apart members 17, connecting members 19 of arcuate form and of substantially the same radial width as the members 17 are employed, the 30 end portions of the members 19 being provided with a dovetail 21 which is adapted to interfit with a corresponding groove 21^a provided in the upper ends of the members 17. When the members 19 are placed in 35 their proper operative positions, with their ends engaging the ends of the members 17, substantially as illustrated in Fig. 1 of the drawings, a substantially self-supporting arch is provided by the built-up members 40 17 and 19. The members 17 on the opposite ledges 18 are located in staggered relation relatively to each other, so that, when a plurality of members 17 and the connecting members 19 are built up, substantially as illustrated in Figs. 1 and 2 of 45 the drawings, the resistor members, consisting of two of the extensions of the members 17 and the intervening member 19, are in series-circuit relation with each other and these sets are in series-circuit relation with corresponding sets located adjacent thereto at each side thereof. Refractory insulating blocks 22 are located between the members 17 and are of a thickness substantially equal 50 to the width of a slot 23 located between the two extensions of the members 17.

In order to provide means to conduct current to and from the ends of the built-up heating element, I provide a refractory block 60 24 of suitable shape to engage the end members 17. Elongated refractory electrodes 25 extend respectively through each of two opposite furnace walls, their inner ends engaging a depression in the outer surface of 65 the terminal blocks 24 and carrying at their

outer tapering ends metallic water-cooled electric-circuit terminal members 26. In order to insulate the terminal members 26 from the furnace structure, I provide an annular insulating member 27 which may be 70 of asbestos or other similar material and which is located in the surface of the furnace wall surrounding the terminal members 26. As the current traverses the entire set of resistor members of arcuate form in 75 series-circuit relation, the two elongated terminal electrodes 25 and the co-operating terminal members 26 are located in opposite walls of the furnace.

Means for pressing the terminal members 80 26 on the electrode 25 and the electrode 25 against the block 24 comprise a screw-threaded stud 28 which is provided, at its inner end, with an enlarged flange portion 29 which operatively engages the outer surface 85 of a plate 31 of a suitable electrical insulating material located against the outer surface of the electric-circuit terminal 26. A helical spring 32 is located around the member 28, and a nut 33 and a washer 34 90 serve to compress the spring 32 against a substantially stationary member 35. While I have indicated a specific embodiment of a resilient compressing means, I do not wish to be limited thereto, as any suitable or desired compressing means may be employed. The construction of the electric-circuit terminal 26 and its mounting on the electrode 25 is more particularly described and claimed in a copending application, Serial 100 No. 463,221, filed April 21, 1921, by G. M. Little and assigned to the Westinghouse Electric & Manufacturing Company.

In order to permit of easy access to the furnace chamber 16, the roof is made substantially semicircular in contour and comprises two metal members 36 provided with handles 37 which have a hinge connection on the metallic framework 12, as illustrated in Fig. 1 of the drawings. An outer layer 110 38 of any suitable heat-insulating material may be located within the cover members 36, and additional layers 39 and 41 of any suitable refractory heat-insulating and high-temperature-resisting material may be located inside of the lining 38. While the two layers 39 and 41 have been illustrated as being integral in construction, this is not an essential feature of my invention, as it is intended that these shall be built up in 115 any suitable or desired manner, as usually employed in the art, so long as they serve the purpose of not only covering the top of the furnace chamber but also of permitting their being readily removed and replaced. The inner lining 41 may be provided with two relatively small integral extensions 42 so located as to operatively engage the upper ends of the extensions of the members 17 to hold them in their proper operative posi- 120 125 130

tions, not only on the ledges 18 but also to cause the upper end of the members 17 to approach each other and thereby to more closely engage the ends of the members 21.

5 An opening 43 may be provided in one of the walls of the furnace to permit of inserting material to be heat treated into the furnace chamber 16.

Referring more particularly to Figs. 3 10 and 4 of the drawings, I have therein illustrated a modification of the hereinbefore described furnace in which the refractory resistor members are not built up of a plurality of parts which are less than semi-circular in arcuate extent. The heating element comprises a plurality of fiat refractory plates 44, substantially semicircular in arcuate extent, which are located in side-by-side relation. Refractory conducting blocks 45 and refractory electrical-insulating blocks 46 are alternately located between two adjacent members 44, the construction being such that current will traverse the members 44 in series-circuit 20 relation and flow in opposite directions in the adjacent members. If desired, a plurality of members 44 and blocks 45 may be of integral construction, as illustrated in Fig. 11.

30 Means for conducting current to and from the heating element comprise substantially, as hereinbefore described, a refractory terminal block 24 located at each end of the built-up heating element, an elongated refractory electrode 25, a metallic terminal member 26 operatively engaging the outer end thereof and a compressing means indicated in part only but of substantially the same construction as hereinbefore described 40 in connection with the furnace illustrated in Figs. 1 and 2. As all of the other features of the furnace are substantially as hereinbefore described, it is not deemed necessary to describe them in further detail.

45 In Figs. 5 and 6, is disclosed a heating element which comprises, in addition to that illustrated in Figs. 3 and 4, a heating element located thereunder and connected in series-circuit relation therewith. A heating element 46 comprises a plurality of relatively thin, flat, refractory substantially rectangular carbonaceous plates 47 having their flat faces in operative engagement with each other and being connected, at one end, 50 in series-circuit relation with the adjacent end of the upper heating element by means of a refractory bar or plate 48. A substantially similar compressing means may be employed for the heating element 46, as is hereinbefore described in connection with the heating element of substantially semi-circular form and it is believed that further description thereof is unnecessary. The built-up heating element, comprising a plurality of flat, carbonaceous plates resiliently

compressed, is more particularly described and claimed in a copending application, Serial No. 454,776, filed March 23, 1921, by G. M. Little and assigned to the Westinghouse Electric & Manufacturing Company. 70

The heating element comprising the members of substantially U-shape and the connecting members of arcuate form, as illustrated more particularly in Figs. 1 and 2 of the drawings, possesses the advantage 75 that a number of contacts are provided between refractory materials and the individual members are relatively small in arcuate extent.

If it is found that the construction of the members 17 of substantially U-shape is relatively complicated and causes a loss by reason of fracture of some of the members during manufacturing operations, it may be advisable to employ the relatively thin, 80 flat arcuate members 44 which may be easily sawed from a relatively thick-walled tubular member. The substantially semicircular form of the heating element permits of concentrating a relatively large percentage of the heat at substantially the center of the arc provided by the inner surface of the upper heating element, whereby a relatively high-temperature heat zone 85 may be obtained. If a still higher temperature or a greater amount of heat is desired, the modification illustrated in Figs. 5 and 6, may be employed. As the current is forced to traverse the integral members 44, and the built up members 17 and 21 in 90 series-circuit relation and to flow from one side of the furnace chamber to the other and then back again, the length of the current path is relatively large, as compared with the length of the furnace chamber, 95 whereby I obtain a relatively high resistance for the entire current path, thus permitting the use of a supply circuit of relatively high voltage and relatively low current input. 100

110 Various modifications may be made in the device embodying my invention without departing from the spirit and scope thereof, and I desire that only such limitations shall be placed thereon as are imposed by the prior art or are specifically set forth in the appended claims.

I claim as my invention:

1. In an electric-resistance furnace, in combination, a plurality of refractory walls enclosing a furnace chamber, a heating element located in said chamber and comprising a plurality of curved and parallel-extending refractory members of substantially semicircular arcuate extent and having 120 their lower ends supported by certain of said walls, refractory means located at one end of said curved members for electrically connecting them in series-circuit relation, refractory means located at the other ends 125

- of said curved members for maintaining them in substantially parallel relation, terminal electrodes having one end extending through one of said walls and operatively engaging said heating element, and resilient means for maintaining said electrodes in close operative engagement with said heating element.
2. In an electric-resistance furnace, in combination, a plurality of refractory walls enclosing a furnace chamber, a heating element located in said chamber and comprising a plurality of curved and parallel-extending refractory members of substantially semicircular arcuate extent and having their lower ends supported by certain of said walls, refractory means located at one end of said curved members for electrically connecting them in series-circuit relation, refractory means located at the other end of said curved members for maintaining them in substantially parallel relation, terminal blocks located partly beneath and partly at the side of the end refractory members and operatively engaging the same, terminal electrodes operatively engaging said terminal blocks and resilient means for pressing said electrodes, terminal blocks and refractory members in close operative engagement.
3. In an electric-resistance furnace, in combination, a plurality of refractory walls enclosing a furnace chamber, a heating element located in said chamber and comprising a plurality of curved and parallel-extending refractory members of substantially semicircular arcuate extent and having their lower ends supported by certain of said walls, refractory means located at one end of said curved members for electrically connecting them in series-circuit relation, refractory means located at the other end of said curved members for maintaining them in substantially parallel relation, a second heating element comprising a plurality of relatively thin flat refractory plates having their flat faces in operative engagement and located beneath said first named heating element and substantially coextensive therewith, a refractory member for connecting the two heating elements in series-circuit relation, terminal electrodes operatively engaging said heating elements and resilient means for pressing said electrodes into close operative engagement with said heating elements.
4. In an electric-resistance furnace, in combination, a plurality of refractory walls enclosing a furnace chamber, a heating element supported by certain of said walls and comprising a plurality of refractory members each having a pair of parallel-extending curved portions of substantially semicircular arcuate extent, means for so connecting the curved portions of successive refractory members that an electric current will traverse the adjacent portions in opposite directions and resilient means for causing said connecting means to closely engage said refractory members.
5. In an electric-resistance furnace, in combination, a plurality of refractory walls enclosing a furnace chamber, a heating element supported by certain of said walls and comprising a plurality of refractory members each having a pair of parallel-extending curved portions of substantially semicircular arcuate extent, means for so connecting the curved portions of successive refractory members that an electric current will traverse the adjacent portions in opposite directions, resilient means for causing said connecting means to closely engage said refractory members, and a roof for said furnace chamber partly supported by said heating element.

In testimony whereof, I have hereunto subscribed my name this 11th day of April, 1922.

ORA A. COLBY.
